UNITED STATES PATENT OFFICE.

SANDFORD R. WADDELL, OF TORONTO, ONTARIO, CANADA.

DESIGN FOR A FORM FOR BOW-TIES.

58,958.

Specification for Design.

Patented Sept. 6, 1921.

Application filed February 28, 1921. Serial No. 448,614. Term of patent 14 years.

To all whom it may concern:

Be it known that I, SANDFORD R. WADDELL, a subject of the King of Great Britain, residing in the city of Toronto, in the county of York, Province of Ontario, Canada, have invented a new, original, and ornamental Design for a Form for Bow-Ties, of which the following is a specification, reference being had to the accompanying drawing, forming part thereof.

In the drawings—

Figure 1 is a front elevation;
Fig. 2 a rear elevation;
Fig. 3 a plan view of the form; and
Fig. 4 an end elevation of the form showing my new design.

I claim:

The ornamental design for a form for bow ties, as shown.

Signed at Toronto, Canada, this 17th day of February 1921.

SANDFORD R. WADDELL.
